ELECTRIC FLATIRON

Donald E. Dailey, Bryn Mawr, Pa., assignor to
Proctor Electric Company, Philadelphia, Pa., a
corporation of Pennsylvania

Application June 9, 1947, Serial No. 139,533

Term of patent 3½ years

(Cl. D49—6)

To all whom it may concern:

Be it known that I, Donald E. Dailey, a citizen of the United States of America, residing in Bryn Mawr, Delaware County, Pennsylvania, have invented a new, original, and ornamental Design for an Electric Flatiron, of which the following is a specification, reference being had to the accompanying drawings, forming part thereof, in which:

Fig. 1 is a side elevational view of an electric flatiron showing my new design;

Fig. 2 is a top plan view of the same;

Fig. 3 is a front elevational view of the same;

Fig. 4 is a rear elevational view of the same; and

Fig. 5 is a fragmentary plan view taken along line 5—5 of Fig. 1.

I claim:

The ornamental design for an electric flatiron, substantially as shown.

DONALD E. DAILEY.
